UNITED STATES PATENT OFFICE.

ELZA R. DICKEY, OF DUGGER, INDIANA.

STEAM-ENGINE.

1,112,987.

Specification of Letters Patent. Patented Oct. 6, 1914.

Application filed June 16, 1913. Serial No. 774,036.

To all whom it may concern:

Be it known that I, ELZA R. DICKEY, citizen of the United States, residing at Dugger, in the county of Sullivan and State of Indiana, have invented certain new and useful Improvements in Steam-Engines, of which the following is a specification.

This invention relates to an improvement in steam engines.

10 The primary object of the invention is to so construct a reciprocating steam engine that major portion of the pressure and expansive force of the steam will be utilized to generate power.

15 A further object of the invention is to provide a construction in which friction will be reduced to a minimum, and in which the movable parts will be so supported that undue wear will be avoided.

20 A still further object of the invention is to provide means for supplying steam and taking the exhaust from a reciprocating cylinder, whereby the cylinder may be moved freely without danger of leakage of 25 the steam when supplied to the cylinder or removed therefrom.

For a full understanding of the invention, reference is to be had to the following description and accompanying drawings, in 30 which:—

Figure 1 is a side elevation; Fig. 2 is a top plan view; Fig. 3 is a longitudinal section of the cylinder and steam chest; and Fig. 4 is a section taken on the line 4—4 of 35 Fig. 3.

Corresponding and like parts are referred to in the following description and indicated in all the views of the accompanying drawings by the same reference characters.

40 In the drawings, 10 designates the engine base or bed. This base consists of the frame 11 and a transverse web 12, the upper edge of the web being concave to accommodate and aid in supporting the engine cylinder 45 as shown at 13. The side members 14 of the frame 11 are provided at their upper edges with a flange 15 to which are bolted plates 16 which overlie the bed-plate. These plates are secured to the flange 15 by bolts 50 16', the bolts passing through elongated slots in the plates, whereby the plates may be moved laterally.

A cylinder 17 rests upon the web 12 and is disposed to slide in the concave top edge 13 55 thereof, and is provided at each of its sides with spaced ribs 18 between which the plates

16 extend, thereby forming guides for the cylinder which may be conveniently lubricated. A crank shaft 19 is mounted in bearings 20 at the end of the base remote from 60 the cylinder. The shaft 19 is provided with three cranks, the central crank 21 being connected to the yoke 22 of a piston rod 23, and the cranks 24 being disposed on both sides of the crank 21 and in an opposite direction 65 to said crank 21.

The cylinder 17 adjacent its front end 25 is provided on each side with trunnions 26. Rods 27 connect these trunnions respectively with the cranks 24 at the same side 70 of the bed. It will be noted by this construction that when the piston rod 23 is reciprocated, and the crank shaft 19 is rotated, the cylinder will be reciprocated, being guided in its movement by the plates 75 16 and effectually supported against lateral movement.

A steam chest 28 is mounted on the cylinder, the supply of steam to the cylinder being controlled by the valve rod 29 which 80 is connected to a yoke 30. The arms 31 of the yoke 30 extend on both sides of the base 10, and are adjustably connected to the converting rod 32 actuated by the eccentric 33 mounted on the crank shaft 19. 85 A cylindrical steam drum 34 is mounted on the steam chest 28, the steam chest being provided with an opening 35 which communicates with the drum. The drum is disposed to move with the steam chest, and 90 is of a length sufficient to allow for the full stroke of the cylinder. The drum at each end is closed by a plate 36 which supports a packing gland 37.

A steam pipe 38 extends through one 95 gland 37 and supplies steam to the drum, the pipe being provided with perforations 39 intermediate its ends. An exhaust pipe 40 is connected to the steam chest, said pipe being provided with an extension 41 which 100 is mounted to reciprocate in an exhaust drum 42, the drum being provided with a gland 43 at its end which receives the pipe 41.

It will be noted by this construction that 105 when the cylinder reciprocates, the steam drum 34 will slide on the steam supply pipe 38, the supply of steam to the cylinder being controlled in the usual manner. The valve gear is such as to permit of the reciprocation of the steam chest and, at the same time, allow for the proper feeding of 110

the steam to the cylinder. As the cylinder reciprocates, the exhaust pipe will telescope in the exhaust drum and the inlet and outlet of the steam thus accommodates itself 5 to the reciprocation of the cylinder. The many advantages of a construction of this character will be clearly apparent, as it will be seen that the larger portion of the pressure and expansion of the steam is 10 utilized, and that greater power will be generated from a certain steam supply than would be generated if the cylinder were stationary.

Particular attention is called to the peculiar manner of mounting the cylinder, as well as the means for supplying and exhausting the steam from the same. By this construction, friction is reduced to a minimum as the movable parts are so mounted 20 that undue wear is prevented. It will also be seen that the entire structure is such as may be easily and economically manufactured, and that the various parts may be readily assembled, it being noted that the 25 device may be used with all fluid pressure motors.

What I claim is:

1. A steam engine comprising, a cylinder, means to reciprocate the same, a steam chest 20 mounted rigidly on the cylinder, a barrel carried by and movable with the steam chest and communicating therewith, a steam sup-

ply pipe extending through the barrel and provided intermediate its ends with a series of perforations, the barrel being disposed to 35 slide on said pipe, a slide-valve arranged in the steam chest and operable by the means for reciprocating the cylinder, and an exhaust pipe communicating with the steam chest and movable with the cylinder. 40

2. A steam engine comprising, a cylinder, a piston arranged within the cylinder, means for simultaneously reciprocating the piston and the cylinder, a steam chest mounted on and movable with the cylinder, 45 a barrel carried by and movable with the steam chest and communicating therewith, a stationary steam supply pipe extending through the barrel and provided intermediate its ends with a series of perforations, 50 a slide-valve arranged in the steam chest, means whereby the valve will be reciprocated simultaneously with the piston and the cylinder, an exhaust pipe connected with the steam chest, and a barrel in which said 55 exhaust pipe is slidably mounted, the exhaust pipe being movable with the cylinder.

In testimony whereof I affix my signature in presence of two witnesses.
